(57) **CLAIM**

The ornamental design for a combined base and basin for a pedicure foot spa, as shown and described.

DESCRIPTION

FIG. 1 is a front perspective view of our invention;

FIG. 2 is a back perspective view;

FIG. 3 is a right side elevation view;

FIG. 4 is a left side elevation view;

FIG. 5 is a top plan view;

FIG. 6 is a bottom plan view;

FIG. 7 is a front elevation view; and,

FIG. 8 is a back elevation view.

The broken lines immediately adjacent the shaded areas represent the bounds of the claim, while all other broken lines are directed to environment and are for illustrative purposes only; the broken lines form no part of the claimed design.

1 Claim, 3 Drawing Sheets
